US00D575990S

(12) **United States Design Patent**
Altiner et al.

(10) **Patent No.:** **US D575,990 S**
(45) **Date of Patent:** **** Sep. 2, 2008**

(54) **PLATE**

(75) Inventors: **Ayse Beril Altiner**, Chicago, IL (US);
Diane Reinicke, Oskosh, WI (US);
Ayberk Abayhan, Lake Bluff, IL (US)

(73) Assignee: **Solo Cup Operating Corporation**,
Highland Park, IL (US)

(**) Term: **14 Years**

(21) Appl. No.: **29/265,147**

(22) Filed: **Aug. 24, 2006**

(51) **LOC (8) Cl.** **07-01**

(52) **U.S. Cl.** **D7/566; D7/570**

(58) **Field of Classification Search** **D7/354, D7/500, 520, 543, 545, 550.1, 554.2, 554.4, D7/560, 565, 566–568, 570, 584–587, 601, D7/602, 608, 551.1, 571; D9/600, 643, 758, D9/773, 776; D23/201; 131/240.1; 206/457, 206/557; 220/571, 573.1, 657, 658, 915.1;**
99/339
